UNITED STATES PATENT OFFICE

DON B. MCLOUD, OF DUQUOIN, ILLINOIS

EXPLOSIVE CARTRIDGE

Application filed March 21, 1931. Serial No. 524,235.

This invention relates to an explosive cartridge, and particularly a cartridge for explosive purposes in open pit mining and quarrying for blasting and loosening surface 5 rock and earth. An explosive cartridge of the type of the present invention comprises an outer cloth or canvas covering or container filled with a carbonaceous material such as soot, sawdust, or the like. The outer cloth 10 covering or bag is preferably closed at one end, and after filling with the carbonaceous material, the open end is tied with metal tie wire, and the cartridge then saturated with liquid oxygen, making a highly explosive 15 cartridge. When a cartridge of this character is immersed in the liquid oxygen for saturation, it readily absorbs several times its original weight of the liquid.

In open pit mining operations the blast 20 holes are drilled vertically, and are from four to eight inches in diameter. Water is used in the process of drilling, and at the time of loading or depositing cartridges in the blast holes, the walls of the holes are 25 often wet from top to bottom. In loading a hole with liquid oxygen explosive cartridges, the first cartridge is usually lowered or dropped to the bottom of the hole, the next cartridge is then dropped on top of the first, 30 and this is continued until the required number have been deposited in the hole, after which dirt stemming or filling is placed on top of the charge. A fulminate cap is inserted in one of the cartridges during the 35 loading operation for later detonation. It is desirable to have the cartridges of as large diameter as possible so as to obtain the maximum amount of explosive in the limited loading space afforded in the lower portion of the 40 drill hole. It is also necessary to load liquid oxygen explosive very quickly because when exposed to ordinary temperatures, the liquid oxygen evaporates rapidly, causing deterioration of the cartridge.

An explosive cartridge consisting of a cloth 45 bag of the proper size and shape filled with carbonaceous material has been unsatisfactory, and has been the cause of premature explosions. Such cartridges when saturated with liquid oxygen become soft, flabby, and

misshapen. When lowered or dropped down the drill hole, they frequently lodge before reaching the bottom by contact with a slight projection that may exist in the hole, or by reason of the flabby condition of the cartridge. Upon lodging, the cartridge will 55 freeze tightly to the wet wall of the hole inasmuch as the temperature of the saturated cartridge is approximately 184 degrees below zero Centigrade, this being the temperature 60 of the liquid oxygen, and the cartridge must then be removed or forced down quickly into the hole. This is a hazardous undertaking, and loss of life has occurred by prodding 65 lodged cartridges in efforts to disengage them.

An object is to provide a cartridge of the character stated, having the property of being maintained after saturation in true cylindrical form to facilitate handling and to 70 avoid lodging, and which is economical to manufacture and highly efficient for the purpose.

Other objects will appear hereinafter.

The invention consists in the combinations 75 and arrangements of parts hereinafter described and claimed.

The invention will be best understood by reference to the accompanying drawings forming a part of this specification, and in 80 which:

Fig. 1 is a perspective view of the completed explosive cartridge of the present invention;

Fig. 2 is a longitudinal sectional view taken 85 substantially on the line 2—2 of Fig. 1;

Fig. 3 is a sectional view similar to Fig. 2, with the carbonaceous material omitted;

Fig. 4 is a transverse sectional view taken 90 substantially on the line 4—4 of Fig. 2; and

Fig. 5 is a face view of the perforated lining material employed.

As illustrated in the drawings, the preferred embodiment of the invention comprises an outer cloth container which is preferably composed of strong heavy cloth, woven so as to be sufficiently porous to allow saturation with liquid oxygen. As shown, this outer container or bag is sewed in such manner that when filled or packed, the 100

cartridge will assume a cylindrical shape. The closed end 8 is preferably conical to facilitate deposit in a blast hole, and after filling, the open end is gathered and tied with tie wires 9, leaving a loose projecting portion 10 which is grasped in handling.

A particular feature of the present invention is the employment of a lining material 11 which is preferably bent into cylindrical form and inserted within the outer cloth bag in contact with the inner surface of the bag, preliminary to filling with carbonaceous material. It is desirable to have this lining material of sufficient strength and stiffness to maintain the filled cartridge in a smooth, compact cylindrical form, and the lining material should also prevent crumpling or rupture under ordinary field conditions. This lining material may consist of strawboard, chipboard, pulpboard, cardboard, juteboard, or pressboard, of the sufficient strength and rigidity. It is necessary, however, that the material be sufficiently flexible to permit of bending into cylindrical form.

In general use, strawboard of .025 caliper has proved very satisfactory. In making the liner, strawboard is cut into a sheet having a length equal to the length of the cylindrical portion of the cartridge when filled, and a width approximately two inches greater than the circumference of the filled cartridge. The invention is especially adapted for use in cartridges ranging from three to seven and one-half inches in diameter, and prior to insertion of the lining material, it is perforated with a plurality of holes or openings. Strawboard or equivalent material having the stiffness and rigidity stated is not sufficiently porous, and would therefore obstruct saturation with liquid oxygen. To allow for such saturation, the lining material is provided with a plurality of perforations or openings 12. These openings or perforations may be round, as shown, square, or any desired shape, and are preferably disposed approximately two inches apart when providing round openings each three-eighths of an inch in diameter. Smaller openings may be provided with relatively closer spacing when employing a thin cardboard, for example, to avoid weakening the liner so that it might crumple or break in service.

Consequently, the dimensions given may be varied while using approximately the same proportion between the spacing and the size of the openings. If the perforations are too large, the carbonaceous material of the cartridge may bulge or extrude through the openings if the cartridge is tightly packed, which would tend to defeat the purpose of making a smooth, rigid cartridge to avoid lodging in a drill hole. Rapidity and economy in manufacture is attained by overlapping the lining material when cylindrical-

ly formed and inserted in the cloth container, as shown at 13 in Fig. 4.

By interposing a lining material of the character stated, which is relatively stiff yet sufficiently flexible to be bent into cylindrical shape, between the outer cloth container and the carbonaceous filler, there is provided a cartridge that is smooth, rigid, and formed to hold a true cylindrical shape after saturation. The perforations described are ample to allow for sufficiently rapid saturation with the liquid oxygen, and the ease with which the cartridge can be handled in the field, reduces loading time and thereby renders the explosive more efficient when detonated.

While I have described and illustrated the preferred form of construction for carrying my invention into effect, this is capable of variation and modification without departing from the spirit of the invention. I, therefore, do not wish to be limited to the precise details of construction as set forth, but desire to avail myself of such variations and modifications as come within the scope of the appended claims.

What I claim as new and desire to secure by Letters Patent is:

1. An explosive cartridge of the character described, adapted to be saturated with liquid oxygen, comprising an outer cloth container sewed in such manner as to assume a cylindrical shape when filled or packed, a filler of carbonaceous material, and a lining material interposed between said container and said filler, said lining material composed of chipboard, strawboard, pulpboard, cardboard, juteboard, pressboard, or the like relatively stiff in structure, but of sufficient flexibility to be bent into cylindrical formation for insertion in said container, and also provided with a plurality of perforations for rapid saturation of said filler, said perforations being substantially in the proportion of a two inch spacing between perforations, each of approximately three-eighths inch diameter.

2. An explosive cartridge of the character described, adapted to be saturated with liquid oxygen, comprising an outer cloth container sewed in such manner as to assume a cylindrical shape when filled or packed, a filler of carbonaceous material, and a lining material interposed between said container and said filler, said lining material composed of strawboard of substantially twenty-five-thousandths caliper, and provided with a plurality of spaced perforations for rapid saturation of said filler.

3. An explosive cartridge of the character described, adapted to be saturated with liquid oxygen, comprising an outer cloth container sewed in such manner as to assume a cylindrical shape when filled or packed, a filler of carbonaceous material, and a lining material interposed between said container and said filler, said lining material composed of straw-

board of substantially twenty-five-thousandths caliper, and provided with a plurality of spaced perforations for rapid saturation of said filler, said perforations being substantially in the proportion of a two inch spacing between perforations, each of approximately three-eighths inch diameter.

4. A lining material for an explosive cartridge of the character described, comprising a sheet of strawboard, of substantially twenty-five-thousandths caliper, and provided with a plurality of spaced perforations substantially in the proportion of a two inch space between perforations, each of approximately three-eighths inch diameter.

5. An explosive cartridge of the character described, adapted to be saturated with liquid oxygen, comprising an outer cloth container sewed in such manner as to assume a cylindrical shape when filled or packed, a filler of carbonaceous material, and a lining material interposed between said container and said filler, said lining material composed of chipboard, pulpboard, cardboard, juteboard, pressboard, strawboard, or the like, of sufficient flexibility to be bent for insertion in said container, and also provided with a plurality of perforations for rapid saturation of said filler.

30 6. An explosive cartridge of the character described, adapted to be saturated with liquid oxygen, comprising an outer cloth container sewed in such manner as to assume a cylindrical shape when filled or packed, a filler of carbonaceous material, and a lining material interposed between said container and said filler, said lining material composed of chipboard, pulpboard, cardboard, juteboard, pressboard, strawboard, or the like, relatively stiff in structure, but of sufficient flexibility to be bent into cylindrical formation for insertion in said container, and also provided with a plurality of perforations for rapid saturation of said filler.

45 In testimony whereof I have signed my name to this specification.

DON B. McCLOUD.
